No. 896,549.

PATENTED AUG. 18, 1908.

I. JOHNSON.

RAIL JOINT AND FASTENER.

APPLICATION FILED NOV. 27, 1907.

UNITED STATES PATENT OFFICE.

IRVIN JOHNSON, OF PERRYOPOLIS, PENNSYLVANIA, ASSIGNOR OF ONE-HALF TO NELSON R. MARTIN, OF PERRYOPOLIS, PENNSYLVANIA.

RAIL JOINT AND FASTENER.

No. 896,549.

Specification of Letters Patent. Patented Aug. 18, 1908.

Application filed November 27, 1907. Serial No. 404,129.

To all whom it may concern:

Be it known that I, IRVIN JOHNSON, a citizen of the United States of America, residing at Perryopolis, in the county of Fayette and State of Pennsylvania, have invented certain new and useful Improvements in Rail Joints and Fasteners, of which the following is a specification, reference being had therein to the accompanying drawing.

10 This invention relates to rail joints and fasteners, and the primary object of the invention is to provide a novel seat or chair for the confronting ends of two rails.

15 Another object of this invention is the provision of positive and reliable means for firmly retaining the confronting ends of two rails upon a seat or chair.

20 A further object of this invention is to provide a connection for rails that will prevent lateral and vertical displacement of the same.

A still further object of this invention is to provide a simple and inexpensive rail connection that will freely allow the expansion and contraction of said rails.

25 A still further object of this invention is to provide a rail fastener that can be easily and quickly assembled for holding the confronting ends of two rails, the fastener being free from danger of injury by rolling stock traveling over the rails held by said fastener.

30 With these and other objects in view which will more readily appear as the invention is better understood, the same consists in the novel construction, combination and arrangement of parts to be presently described and then specifically pointed out in the appended claims.

35 In the drawings: Figure 1 is a cross sectional view of my joint, Fig. 2 is a plan of the 40 detachable splice bar, Fig. 3 is an elevation of the same, Fig. 4 is a plan of the rail seat or chair, and Fig. 5 is an elevation of the same, partly broken away.

To put my invention into practice, I construct a rail seat or chair comprising a plate 1 having an integral splice bar 2, provided with detachable pins 3, for engaging in the ordinary bolt openings 4 formed in the webs 5 of rails 6. The pins 3 are mounted in suitable 50 sockets 3^a provided therefor in the splice bar 2. The plate 1 upon its opposite edge is provided with a tapering flange 7, providing a tapering tongue-way 8, this tongue-way being partially formed in the plate 1, as indicated at 9. The plate 1 is also provided,

with a plurality of depending prongs 10 for engaging in a tie or sleeper. Besides these prongs the plate upon the splice bar side thereof is provided with notches 11 for spikes, and adjacent to the tongue-way 8 are elongated openings or slots 12 for spikes.

In connection with the seat or chair I use a detachable splice bar 14, this splice bar having a tapering tongue 15 adapted to engage in the tongue-way 8. The splice bar also has 65 an overhanging edge 16 for protecting the flange 7, and spike openings 17 adapted to register with the spike openings or slots 12.

After the detachable splice bar 14 has been placed in position to firmly brace the heads 70 of the rails 6 and retain said rails upon the seat or chair, spikes are driven through the openings 17 to hold the detachable splice bar 75 in position. These spikes, which I have deemed it unnecessary to illustrate, also assist in retaining the seat or chair in position upon a tie or sleeper, and in conjunction with the depending prong 16, are adapted to prevent a lateral displacement of said chair or seat with relation to its support. In some 80 instances the depending prongs can be dispensed with.

I desire to call particular attention to certain novel features embodied in my rail joint, first, the pins designated 3 can be dispensed 85 with at any desired time, particularly in case of a broken rail; second, in providing the plate 1 for supporting the confronting ends of two rails, I dispense with the use of wires or electrical conductors between the ends of 90 rails, the plate insuring a positive electrical connection; third, the elongated openings or slots 12, allow the detachable splice bar 14 to be adjusted at any desired time with relation to the plate 1, it only being necessary to 95 withdraw the spikes, drive the splice bar 14 inward, and then re-drive the spikes to retain said splice bar in its newly adjusted position.

I do not care to confine myself to the use 100 of the chair or seat in connection with wooden ties or sleepers, as bolts and nuts or similar fasteners (not shown) can be used in lieu of spikes for securing the chair or seat to a metallic tie.

105 The novel construction of my fastener does not necessitate the changing of the present type of rails, as the ordinary bolt openings can be used to receive the pins 3 of the splice bar 2. This splice bar is preferably 110

used on the outer side of the rail, to prevent a track from spreading and to brace the rails upon curves.

Having now described my invention what I claim as new, is:—

- 5 1. In a rail joint, the combination with rails having openings formed in the webs thereof, of a chair comprising a supporting plate for the base of the rail, a splice bar formed integral with the plate and overlapping one side of the base of the rail and engaging the head of the rail, the upper portion of the splice bar beveled inwardly whereby the outer upper edge of the splice bar will be flush with the side of the head of the rail said splice bar free of the edge of said side of the base which it overlaps, a plurality of pins carried by said splice bar and adapted to extend in the openings of said webs, a tapering flange formed on one side of the plate, that portion of the plate adjacent to said flange cut away to provide in connection with the flange a tapering tongue-way, said tongue-way arranged at a point removed from the side edge of the base of the rail, a detachable splice bar engaging the head of the rail and having its outer face at the top beveled inwardly whereby the outer edge of said splice bar will be flush with the side of the head of the rail, said detachable splice bar having a tongue adapted to engage in said tongue-way, said tongue free of contact with the base of the rail, said detachable splice bar further provided with an outer depending portion which projects from and incloses that end of the plate provided with the flange, a plurality of prongs carried by said plate, and means for securing said detachable splice bar in a fixed position with relation to said plate,
- 10 15 20 25 30 35 40 45 50 55 60 65 70 75 80 85 90 95 100
2. In a rail joint, the combination with rails having openings formed in the webs thereof, of a chair comprising a supporting plate for the base of the rail, a splice bar formed integral with the plate and overlapping one side of the base of the rail and engaging the head of the rail, the upper portion of the splice bar beveled inwardly whereby the outer upper edge of the splice bar will be flush with the side of the head of the rail said splice bar free of the edge of said side of the base which it overlaps, a plurality of pins carried by said splice bar and adapted to extend in the openings of said webs, a tapering flange formed on one side of the plate, that portion of the plate adjacent to said flange cut away to provide in connection with the flange a tapering tongue-way, said tongue-way arranged at a point removed from the side edge of the base of the rail, a detachable splice bar engaging the head of the rail and having its outer face at the top beveled inwardly whereby the outer edge of said splice bar will be flush with the side of the head of the rail, said detachable splice bar having a tongue adapted to engage in said tongue-way, said tongue free of contact with the base of the rail, said detachable splice bar further provided with an outer depending portion which projects from and incloses that end of the plate provided with the flange, and means for securing said detachable splice bar in a fixed position with relation to said plate, each of said splice bars provided with inwardly extending offsets at the top and bottom whereby the body portion of the splice bars are prevented from engaging with the tread of the rail.

In testimony whereof I affix my signature in the presence of two witnesses.

IRVIN JOHNSON.
